R. P. WRIGHT,
COMBINED STRIPPER AND PRESSURE RELEASE,
APPLICATION FILED DEC. 2, 1916.

1,224,054.

Patented Apr. 24, 1917.

UNITED STATES PATENT OFFICE.

REA P. WRIGHT, OF WASHINGTON, DISTRICT OF COLUMBIA, ASSIGNOR TO JOHN FRANCIS HEMENWAY, OF NEW YORK, N. Y.

COMBINED STRIPPER AND PRESSURE-RELEASE.

1,224,054.

Specification of Letters Patent. Patented Apr. 24, 1917.

Application filed December 2, 1916. Serial No. 134,839.

To all whom it may concern:

Be it known that I, REA P. WRIGHT, a citizen of the United States, residing at Washington, in the District of Columbia, have invented certain new and useful Improvements in Combined Strippers and Pressure-Releases, of which the following is a specification, reference being had therein to the accompanying drawing.

10 This invention relates to certain new and useful improvements in clothes wringers, the object being to provide a combined roller stripper and release whereby the pressure on the pressure rolls will be instantaneously released in case of a foreign object being drawn between the rolls when in operation.

Another object of my invention is to provide releasing mechanism in which a stripper board is employed for operating the 20 means for holding the pressure in predetermined position.

Another object of my invention is to provide a release in which the top bar is movably mounted within the side bars of the 25 frame and held in predetermined position by a resilient member which is expanded by the upward movement of the stripper board.

Other and further objects and advantages of the invention will be hereinafter set forth 30 and the novel features thereof defined by the appended claims.

In the drawings,

Figure 1 is a side elevation partly in section of a clothes wringer showing the application 35 of my improved construction of combined stripper and release thereto.

Fig. 2 is a section taken on line 2-2 of Fig. 1.

Fig. 3 is a detail perspective view of the 40 stripper.

Fig. 4 is a vertical section through a slightly modified form of combined release and stripper; and

Fig. 5 is a detail perspective view of the 45 keeper and the resilient retaining member.

Like numerals of reference refer to like parts in the several figures of the drawings.

In carrying out my invention I employ a frame 1 having slotted side bars 2 in which 50 are mounted superposed bearings carrying pressure roll shafts 3 and 4 which are provided with the usual pressure rolls 5 and 6, the upper bearing being provided with a

spring support 7 on which is mounted a coil pressure spring 8. Mounted on the coil 55 pressure springs 8 are bearing plates 9 carried by pressure bar 10 adapted to be engaged by pressure screws 11 mounted in threaded boxes 12 carried by a movably mounted top bar 13, arranged within slotted 60 upper portions of the side bars 2, as clearly shown in Fig. 1.

Secured over the upper ends of the side bars 2 of the wringer frame are plates 14 provided with substantially inverted T- 65 shaped slots 15, into which are adapted to extend substantially T-shaped ends 16 of a spring 17 mounted in guide members 18 carried by the top bar 13, as clearly shown in Figs. 1 and 2, said spring having a centrally 70 disposed bowed portion 19. When the ends of the spring are in position within the slots of the plates 14 as shown in Fig. 1, the top bar is held in predetermined position within the wringer frame in order to allow the 75 pressure screws 11 to be adjusted so that the desired pressure on the pressure rolls can be obtained.

Mounted above the upper rolls 6 is a stripper board 20, the ends thereof extending 80 slightly into the slots of the side bars of the frame, and are provided with shoulders 20¹ carrying adjusting screws 20² resting on the upper bearing for supporting the stripper board with its lower edge adjacent the upper pressure roll. The stripper board 20 is provided with a centrally disposed bifurcated stem 21 which embraces the pressure bar 10 and the bowed portion 19 of the spring 17 as shown in Figs. 1 and 2. The 90 bifurcations of the bifurcated stem are provided with openings 22 adapted to receive a pin 23 disposed beneath the bowed portion 19 of the spring 17 so that when the stripper board 20 is moved upwardly beyond the ordinary distance of travel caused by the passage of clothes between the pressure roll, the spring will be elongated so as to move the T-shaped heads 16 out of the T-shaped slots 15 of the plates 14, which allows the 100 top bar to move vertically within the wringer frame, so as to release the pressure on the pressure roll.

The stripper 20 is normally held slightly above the upper pressure roll 6 and prevents 105 the clothes from winding around the same

in their passage therethrough. By providing the stem of the stripper with a series of openings the pin 23 can be adjusted in respect to the bowed portion of the spring 5 as the stripper board wears, or the device can be adjusted so that the top bar can be released by the separation of the pressure rolls in the passage of different thicknesses of clothes therethrough.

- 10 In the modifications shown in Fig. 4, I provide a wringer frame 24 having the usual superposed pressure rolls 25 and 26 in the upper roll of which is mounted a stripper 27, carrying a bolt 28, on which is adjustably mounted a trip member 29 which is locked in adjustable position by thumb nut 30, said trip member having a laterally projecting portion 31 extending under the bowed portion of the spring 32 carried by 15 the movably mounted top bar 33, the spring being constructed substantially as shown in the preferred form so as to hold the top bar in predetermined position within the wringer frame.
- 20 25 From the foregoing description it will be seen that I have provided a combined clothes stripper, and pressure release in which the stripping member operates, the retaining means for the removably mounted top bar, so that the top bar is released when the stripper is moved vertically by the separation of the pressure rolls.

I claim:

1. A clothes wringer comprising a frame 35 having pressure rolls and pressure means for said rolls mounted therein, a movably mounted pressure screw carrying member mounted in said frame, means for holding said movably mounted pressure screw carrying member in predetermined position, a stripper member mounted in said frame contacting with said retaining means on the separation of said rolls for releasing said means.
- 40 45 2. A clothes wringer comprising a frame having pressure rolls and pressure means for said rolls mounted therein, a movably mounted pressure screw carrying member mounted in said frame, a pressure screw carried by said member for adjusting said pressure means, a resilient member for holding said pressure screw carrying member in predetermined position within said frame, a stripper mounted in said frame adjacent 55 one of said pressure rolls, and means carried by said stripper member coacting with said resilient member for expanding said resilient member on the separation of said pressure rolls for releasing said pressure 60 screw carrying member.
- 50 55 60 65 3. A clothes wringer comprising a frame having pressure rolls and pressure means for said rolls mounted therein, a top bar movably mounted in said frame, a resilient member carried by said top bar for nor-

mally holding said top bar in predetermined position within said frame, and a stripper member mounted in said frame above one of said pressure rolls for expanding said resilient member on the separation, 70 of said rolls for releasing said top bar.

4. A clothes wringer comprising a frame having pressure rolls and pressure means for said rolls mounted therein, keepers carried by the side bars of the said frame, a top bar movably mounted within said frame, a resilient member carried by said top bar cooperating with said keepers for normally holding said top bar in predetermined position within said frame, a stripper board 75 mounted in said frame adjacent the upper pressure roll and means carried by said stripper board for expanding said resilient member on the separation of said rolls for releasing said top bar.

5. A clothes wringer comprising a frame having pressure rolls and pressure means for said rolls mounted therein, a top bar movably mounted within said frame, keepers carried by the side bars of said frame, a resilient member carried by said top bar cooperating with said keepers for normally holding said top bar in predetermined position within said frame, a stripper member 80 movably mounted within said frame adjacent the upper pressure roll and means carried by said stripper member for expanding said resilient member on the separation of said rolls for releasing said top bar.

6. A clothes wringer comprising a frame having pressure rolls and pressure means for said rolls mounted therein, a top bar movably mounted in said frame, a resilient member carried by said top bar for normally holding the top bar in predetermined position within said frame, a stripper member 85 mounted adjacent the upper pressure roll having a stem embracing said resilient member, a pin adjustably mounted within said stem and adapted to contact with said resilient member on the separation of the said rolls for expanding said resilient member to release said top bar.

7. A clothes wringer comprising a frame having pressure rolls and pressure means for said rolls mounted therein, a top bar movably mounted in said frame, means carried by said top bar for holding said top bar in predetermined position within said frame, a stripper member mounted adjacent the upper pressure roll and means carried by said stripper member engaging the retaining means on the separation of the 110 said pressure rolls for releasing said top bar.

8. A clothes wringer comprising a frame having pressure rolls and pressure means for said rolls mounted therein, keepers carried by the side bars of said frame, a top 115 120 125 bar

- bar movably mounted in said frame having pressure screws for adjusting said pressure means, a resilient member carried by said top bar coöperating with said keepers for holding said top bar in predetermined position within said frame, a stripper member mounted adjacent the upper pressure roll having a stem embracing said resilient member and a pin adjustably mounted in said stem adapted to engage said resilient member on the separation of said rolls for expanding said resilient member to release said top bar.
9. A clothes wringer comprising a frame having pressure rolls and pressure means for said rolls mounted therein, a movably mounted top bar carrying pressure screws for adjusting said pressure means, a resilient member for holding said top bar in predetermined position, a stripper member adjustably mounted above the upper pressure roll, and a member adjustably carried by said stripper member coacting with said resilient member on the separation of the said rolls for releasing said top bar.
10. A clothes wringer, comprising a frame having pressure rolls and pressure means for said rolls, a resilient member having means for normally holding said pressure means in predetermined position, and means actuated by the separation of said rolls engaging said resilient member for releasing said pressure means.
11. A clothes wringer, comprising a frame having pressure rolls and pressure means for said rolls, a resilient member having means for normally holding said pressure means in predetermined position, and adjustable means actuated by the separation of said rolls engaging said resilient member for releasing said pressure means.
12. A clothes wringer, comprising a frame having pressure rolls and pressure means for said rolls, a resilient member having means for normally holding said pressure means in predetermined position, and a member arranged in the path of travel of one of said pressure rolls and operated thereby on the separation of said rolls en-
- gaging said resilient member for releasing said pressure means.
13. A clothes wringer, comprising a frame having pressure rolls and pressure means for said rolls mounted therein, a movable member carrying means for adjusting said pressure means, means for holding said movable member in predetermined position, a stripper member adjustably mounted in said frame in respect to one of said pressure rolls, and means carried by said stripper member engaging said retaining means on the abnormal separation of said rolls for releasing said movable member.
14. A clothes wringer, comprising a frame having pressure rolls and pressure means for said rolls mounted therein, means for normally holding said pressure means in predetermined position, a stripper member adjustably mounted in said frame in respect to one of said pressure rolls, and means carried by said stripper member engaging said retaining means on the abnormal separation of said rolls for releasing said pressure means.
15. A clothes wringer, comprising a frame having pressure rolls and pressure means for said rolls mounted therein, means for normally holding said pressure means in predetermined position, a stripper member mounted in said frame adjacent one of said pressure rolls, and adjustable means carried by said stripper member engaging said retaining means on the abnormal separation of said rolls for releasing said pressure means.
16. A clothes wringer, comprising a frame having pressure rolls, means for holding said rolls in contact under tension, and a stripper member movably mounted in said frame adjacent one of said rolls for releasing said tension means on the abnormal separation of said rolls.

In testimony whereof I hereunto affix my signature in the presence of a witness.

REA P. WRIGHT.

Witness:
N. CURTIS LAMMOND.
